UNITED STATES PATENT OFFICE

163,486

LAWN EDGING MACHINE

James Curtis Sanford, Dallas, Tex.

Application October 28, 1949, Serial No. 5,750

Term of patent 7 years

(Cl. D40—1)

To all whom it may concern:

Be it known that I, James Curtis Sanford, a citizen of the United States, residing at Dallas, in the county of Dallas and State of Texas, have invented a new, original, and ornamental Design for a Lawn Edging Machine, of which the following is a specification, reference being had to the accompanying drawing, forming part thereof:

Figure 1 is a front perspective view of a lawn edging machine embodying my new design.

Figure 2 is a front elevational view, and

Figure 3 is a side elevational view.

I claim:

The ornamental design for a lawn edging machine, substantially as shown.

JAMES CURTIS SANFORD.
